Specification of Letters Patent.

Patented July 9, 1918.

Application filed August 24, 1912. Serial No. 716,939.

To all whom it may concern:

Be it known that I, ARTHUR F. POOLE, of Chicago, county of Cook, and State of Illinois, have invented certain new and useful 5 Improvements in Calculating-Machines, of which the following is a specification.

In my Patent No. 1,198,050, issued September 12, 1916, is disclosed a calculating machine. This machine is combined with a 10 Remington typewriter, having the ordinary Gorin tabulator attachment, and is provided with a set of columnar totalizers and a universal totalizer. The columnar totalizers are mounted on a bar moved with the carriage. The universal totalizer is adapted 15 to be connected to any of the columnar totalizers and will move in unison therewith during the insertion of a number; consequently the same number can be entered simultaneously in both a columnar and the universal 20 totalizers. Both the columnar and universal totalizers are provided with tabulating means which bring them to the proper decimal place, prior to the insertion of any 25 number. The tabulating means is actuated by the ordinary tabulating keys of the typewriter. While all the power to bring the columnar totalizers to a required decimal place is furnished by the typewriter carriage 30 spring, the power necessary to bring the universal totalizer to its position comes from the tabulating keys themselves.

My present invention is an improvement on the above described machine. 35 One of the objects of my invention is a power tabulated universal totalizer. To this end the universal totalizer is adapted to be connected to preferably a continuously running motor on the actuation of any tabulating key. The universal totalizer is therefore tabulated to a position determined by the particular key operated. The power is then automatically disconnected. Thus the key only initiates the tabulation of the universal totalizer. The necessary power for 40 this operation does not come from the key but from the motor. Tabulation of the universal totalizer puts, therefore but a small additional load on the normal action of the 45 tabulating keys, the tabulating keys simply connecting such power to the universal totalizer, thereby making their action more

easy, than in the machine described in my above mentioned application.

Another object of my invention is the particular constant aggregate motion linkage used to tabulate the universal totalizer. 55

Another object of my invention is to provide a power driven carriage return, for the typewriter carriage carrying the columnar 60 totalizers. To this end a source of power such as a continuously running motor is provided with a key controlled mechanical clutch, so that the motor can be connected to the carriage to return it. 65

Another object of my invention is the linkage connecting the carriage return key with the clutch so that upon the carriage reaching a predetermined position it is disconnected from the source of power regardless of the position of the carriage return key at that time. 70

Another object of my invention is an elastic stop for said carriage so that when it reaches the end of its return, it comes to 75 rest without a jar.

There are several other objects of this invention which will be explained in the body of the specification.

The invention is illustrated by the accompanying drawings forming part of the specification. There are a large number of parts in this machine which are in no way different in operation from the machine described in the application above mentioned, and 80 since these form no part of the present invention and would only tend to confuse the drawings, they have been accordingly omitted. 85

Figure 1 is a rear elevation of the machine. 90

Fig. 2 is the left elevation of part of the machine.

Fig. 3 is a top view of the rear of the machine. 95

Fig. 4 is the right elevation of the machine.

Fig. 5 is a detail of the particular form of clutch employed in connection with the carriage return. 100

Figs. 6 and 7 show details of the clutch used with the power tabulating device.

Fig. 8 shows the constant aggregate motion linkage in its normal position.

Fig. 9 shows the same in an operated position.

Fig. 10 is a detail showing the locating bars of the constant aggregate motion link 5 age in contact with a tabulator stop.

My invention consists broadly of a power driven carriage return and a power driven tabulating device for the universal totalizer of the machine. Both of them are driven 10 from the same source of power.

I will first describe the carriage return. Mounted on the framework 1, (Figs. 1 and 2) is a shaft 2 running in suitable bearings and connected to a source of power, preferably an electric motor. This motor is not 15 shown in the drawings since it is well known and would simply tend to confuse them. The shaft 2 is so connected to the source of power as to turn in the direction 20 of the arrow. Mounted on the shaft 2 is a clutch 2^a, shown in greater detail in Fig. 5. This clutch 2^a consists of a socket 4 rigid with the shaft 2 and a slidably mounted cone 5. Embracing cone 5 is a ball bearing 25 collar 6, pivoted at the points 3 to a fork 7, rigidly mounted on a link 8. This link 8 is adapted to be moved by link 9 pivoted at 28, by link 10 pivoted at 29 or by both of them acting simultaneously. Link 10 is 30 connected through a lever 11 fulcrumed at 51 and twisted link 12, to the carriage return key 13 fulcrumed at 52. It is then evident that if we consider the pivot 28 stationary, a downward pressure on key 13 35 will cause engagement of the cone 5 with socket 4, thus rigidly connecting cone 5 to the shaft 2.

On the cone 5 and rigid with it is a spiral gear 14 engaging with a spiral gear 15 40 mounted on a shaft 16. At the upper end of shaft 16 is a spiral 17 in mesh with a spiral 18 rigid with a shaft 19, on the other end of which is a spur gear 20. The shaft 19 and its associated gears 18 and 20 revolve 45 in a suitable bearing 21 mounted on the framework 1. In mesh with the gear 20 is a rack 22 mounted on the typewriter carriage 25 by means of the stud screws 23. Immediately back of this rack 22, held by the 50 same screws and separated from it by washers 41, is the regular typewriter rack 42. Both of these racks are mounted by means of the stud screws 23, on a swinging arm 43 swinging about fulcrums 44 in the typewriter carriage 25. The spring 45 holds 55 these racks 22 and 42 against a stop 47, which insures correct meshing of the rack 22 with the gear 20, and of the rack 42 with the gear 46, which is the regular spur gear 60 of the typewriter escapement 48. Slots 24 are cut in rack 22 so that it will have a certain amount of longitudinal movement relative to the typewriter carriage 25. It is now evident that if the pivot 28 is stationary 65 and the carriage return key 13 de-

pressed, thereby causing the gear 14 to revolve with the shaft 2, that motion will be transmitted through shaft 16, gears 17, 18 and 20, to the rack 22, and as soon as this rack is moved to the left the length of the slots 24, the typewriter carriage 25 will be moved to the left also.

I will now describe the means for disengaging the cone 5 and thereby stopping the carriage 25. The link 9 is pivoted at 30 on 75 a link 26 fulcrumed to the framework at 27, and it will be observed that in their normal position the points 28, 30 and 27 are in a straight line. Pivoted to link 26 at a point 31, is a link 32 whose upper end is attached 80 to an arm 33 on a jack shaft 34. Rigid with this jack shaft 34 is a lever having a vertical arm 36 and a horizontal arm 35. Mounted on the carriage 25 is a screw 38 whose length is approximately equal to the 85 maximum carriage travel. On this screw 38 is an adjustable nut 37 adapted to contact with the lever arm 36. Returning to the arm 35, it will be seen that it is in contact with an arm 39 fulcrumed at 49 and 90 carrying the bearing of the tabulator governor gear 40. It will be remembered that in the well known action of a typewriter tabulator when any tabulating key of the typewriter is actuated the governor gear 40 95 will engage with the typewriter rack 42, thereby lifting it from engagement with the escapement gear 46, and thus permitting the carriage spring to move the carriage to the right (as viewed from the rear 100 of the machine, see Fig. 1) until it is arrested by a tabulator stop. When this arm 39 is depressed by the arm 35 it will lift the racks 22 and 42 from engagement with their respective gears 20 and 46. At the 105 same time through the consequent depression of link 32, the link 26 is pressed downward thereby breaking the existing toggle between fulcrum 27 and pivot 28, and through the action of the link 9 on the link 110 8 disengaging the clutch 2^a. It will thus be seen that the lever fulcrumed at 34 has two functions, one by depressing the link 32 to disengage the clutch 2^a from the motor, the other by raising the governor gear 40 to 115 lift the racks 22 and 42 from mesh with the gears 18 and 46.

The cycle of operation of the carriage return will then be as follows: Starting with the carriage at some point where the nut 37 120 is not in contact with the arm 36, the key 13 is depressed. It will be observed that since the points 27, 30 and 28 are in a straight line, the lever 8 will turn about the point 28 thereby causing engagement of the clutch 2^a and transmitting the motion of the shaft 2 to the gear 20. As soon as the rack 22 is moved the length of the slots 24, the carriage will move to the left (as viewed 125 from the rear. See Fig. 1.) When nut 37, 130

which it will be remembered is rigid with the carriage 25, strikes the arm 36 thereby moving it in a counter-clockwise direction, two things occur. First the toggle which 5 existed between the points 27 and 28 will be broken, the point 28 moved to the left thereby disengaging the clutch 2^a. Second, under the influence of its momentum the carriage 10 will continue to move to the left thereby further rotating arm 36, and the governor gear 40 will raise the racks 22 and 42 from their respective gears 20 and 46. This motion will be resisted by the spring 45 and 15 the carriage spring 50 until the momentum of the carriage is destroyed, then under the influence of the spring 45 and the carriage return spring 50, the carriage 25 will start to move to the right, and the arm 36 will move toward its normal position. As soon 20 as the arm 36 is returned to the right far enough to allow the racks 22 and 42 to come into engagement with their respective gears 20 and 46, the carriage will be stopped by the escapement wheel 48 of the typewriter. 25 It will be noted that as soon as the power is taken from the carriage, by the disengagement of the clutch 2^a, it is moved against the tension of the spring 45 by its own momentum, and that when this momentum is destroyed and it starts on its return to the right, it will be stopped at a definite point. Thus the carriage will be brought to rest without a jar.

It will be remembered that the rack 22 had 35 longitudinal movement with reference to the carriage 25. This is for the purpose of feeding the paper at each return of the typewriter carriage. In the rack 22 is a pin 53 engaging a lever 54 fulcrumed on the carriage 25 at 55. Pivoted to the lever 54 at 40 56 is a rod 57. This rod 57 is connected by suitable linkage to the regular paper feeding mechanism. Since this mechanism forms no part of my present invention, I have not 45 shown it. It is obvious that each time the carriage is returned by the motor the rack 22 will be moved to the left until it comes to a definite stop, which will be when the paper feeding pawl has advanced the paper, then, 50 rack 22 will move the carriage, until the clutch 2^a is disengaged by the action of nut 37 on arm 36 as before described.

I will now describe the power tabulating mechanism for the universal totalizer. The 55 universal totalizer 60 is mounted on a bar 61, sliding on two rods 62 (Figs. 1 and 4). It is adapted to be connected to the columnar totalizers by a bar 63. As these parts and their functions have been fully described in 60 my application above referred to, I shall not consider them further. As fully explained in this aforementioned application it is necessary when the tabulator carriage carrying the columnar totalizers is tabulated, that the 65 universal totalizer be tabulated also, since

from that point until the number is inserted, the two totalizers move in unison. In my present invention I have provided a constant aggregate motion linkage to tabulate the universal totalizer. The general principle of this linkage is the same as that disclosed and fully explained in application Serial No. 697704, filed May 16, 1912, by Hyman Eli Goldberg. In that application the ordinary tabulator stops of the typewriter serve to locate the tabulatable totalizer by a constant aggregate motion linkage. The same is true in my present invention but the constant aggregate motion linkage is differently arranged, and the power for actuating the same comes from the motor instead of from the tabulator keys themselves.

On the shaft 2 (Figs. 1, 6 and 7) is a worm 64 meshing with a worm wheel 65 rigid with a shaft 66. Loosely mounted on this shaft 66 is a disk 67 carrying on one side a pawl 68, pivoted at 69, and on the other side an eccentric 70. A spring 71 tends normally to throw the point of the pawl 68 into engagement with a ratchet wheel 72. This ratchet wheel 72 is rigid with the shaft 66 and worm wheel 65, and since the motor is continuously moving, the ratchet 72 will be continuously moving in the direction 90 of the arrow also. A slidable piece 73 mounted in the framework 1, has on it projections 74 and 75 in different planes. The pawl 68 has a cam surface 76 which by contact with the projection 74 holds the pawl 68 free from the ratchet wheel 72. If piece 73 is displaced in the direction of the arrow (Fig. 3) until projection 74 is free from the cam 76, the spring 71 will throw the pawl 68 into engagement with the ratchet 72. Consequently disk 67 on which pawl 68 is mounted will revolve with the shaft 2. Assuming the piece 73 to remain in its displaced position during one revolution of disk 67, the cam 76 will come in contact with the projection 75 on the piece 73, and the pawl 68 will be withdrawn from the ratchet 72. The disk 67 will then stop. On the replacement of the slidable piece 73 to its normal position, the cam 76 will be released from 110 the projection 75 and will immediately be engaged by projection 74. It is now evident that displacement of the slidable piece 73, from its normal position, will cause the disk 67 to be turned by the motor through one 120 revolution and said disk will thereupon disconnect itself from the motor and remain so until a subsequent displacement of the slid- able piece 73. It will also be observed that if the slidable piece 73 is replaced in its nor- 125 mal position before the disk 67 has completed its revolution the disk 67 will stop as before, except that it will be the projection 74 that will now stop it instead of the pro- jection 75. This clutch mechanism will be 130

recognized as the same in principle as the nonrepeating clutch used in punch presses.

Fulcrumed at 77 (Figs. 1, 8 and 9) in the framework is a lever 78 having a slot which 5 embraces the eccentric 70, and a roller 80 pivoted at 79. Consequently each displacement of the slideable piece 73 and consequent revolution of the eccentric 70, will cause an up and down motion of the roller 80. Leaving for a moment this part of the mechanism 10 I will now describe the constant aggregate motion linkage which tabulates the universal totalizer and is actuated by the roller 80.

A shaft 81 is fulcrumed in the framework 15 and carries on it in different planes two loosely mounted arms 82 and 83. These arms are connected by two equal links 84 and 85 pivoted at 86 and 87 respectively. Links 84 and 85 are joined in a pivot 58 and 20 also at this point is pivoted a cam 93. This cam 93 has three cam surfaces 88, 90 and 91. Cam surface 88 engages with a roller 89 rigid with the shaft 81. Cam surface 90 engages with the roller 80. Cam surface 91 25 engages with the shaft 81. The cam surface 91 is the width of the shaft 81 and ends in a semicircular surface about a point 92. The throw of the roller 80 is such that at the end of its upstroke the point 92 will be brought 30 into coincidence with the center of the shaft 81. The distance from the shaft 81 to the center of the roller 89 is less than the vertical throw of the roller 80. Consequently when the cam 93 is raised to its uppermost position 35 the cam surface 91 will embrace the roller 89 also. However, in this position the whole linkage has still freedom of rotation about the shaft 81, since the cam surface 90 against which the roller 80 is in contact at 40 that time, is a semicircle about the point 92 and 92 is at that time in coincidence with the center of the shaft 81. In order to locate this linkage in a definite position when the cam 93 is in its uppermost position, a locating bar 94 is pivoted at 95 on the upper end 45 of 82, and a locating bar 96 is pivoted at 97 on the upper end of 83. These bars are guided in suitable slots in the piece 59 rigid with the framework.

50 The bar 96 has a projection 98 on one end, this projection 98 extends into the plane of the bar 94, (Fig. 10). When the cam 93 is raised to its uppermost position, by means of the roller 80, the pivots 95 and 97 are in 55 approximate alignment, (Fig. 9). The length of the locating bars 94 and 96 are such that when the bars are in the position shown in Fig. 9, the space between the projection 98 and the end of the bar 94 is just 60 equal to the width of a tabulator stop, 113. This is clearly shown in Fig. 10. It will be now evident that if any tabulator stop is 65 protruded and the slideable piece 73 actuated, thus causing an up and down motion of the roller 80, the bars 94 and 96 will come in

contact with the opposite sides of the protruded tabulator stop. Remembering that the linkage composed of links 82, 83, 84 and 85 has freedom of motion about the shaft 81, and when this linkage is in its operative 70 position the space between the end of the bar 94 and projection 98 is equal to the width of a tabulator stop, it will be seen that when operated this linkage will be located in a definite position according to the 75 position of the tabulator stop embraced by the bars 94 and 96. Now the cam 93 is then constrained at two points. One at 58 the junction of the links 84 and 85, which is in a line joining the pivot 95 with the shaft 81, 80 and the other at the shaft 81. Consequently this cam 93 is definitely located in a position corresponding to some particular tabulator stop, and the roller 89 which it will be remembered is rigid with the shaft 81, will be 85 brought to a definite position also. Therefore we have the following condition of affairs: When a tabulator stop is protruded into the plane of the bar 94 and the projection 98, and the slideable piece 73 actuated, 90 the roller 89 rigid with the shaft 81 will be brought to some definite position depending upon the particular tabulator stop which has been protruded.

The connection between the roller 89 and 95 the universal totalizer 60 is easily traced. It will be remembered that the roller 89 is rigid with the shaft 81. Parallel to the shaft 81 is a shaft 99 fulcrumed in the framework and having rigid with it, an 100 arm 100. On shaft 81 is an arm 98 equal in length to the arm 100. Connecting arms 98 and 99 is a link 105 equal in length to the distance between the shafts 81 and 99. Consequently the framework, arms 98 and 105 100, and link 105 form a parallelogram linkage and the angular motion of shaft 99 will be the same as the angular motion of shaft 81. An arm 101 is rigid with the shaft 99 and is connected by a link 102 to the bar 61. 110 It will be remembered that this bar carries the totalizer 60. The arm 101 is equal in length to the distance between the shaft 81 and the pivot 95, and parallel to the line joining the centers of the shaft 81 and the 115 roller 89. Since, when the locating linkage is actuated, the angular motion of shaft 81 is equal to the angular motion of pivot 95 about said shaft, the motion of the totalizer bar 61 will be equal in direction and amount 120 to that of the pivot 95, which is to say that the totalizer 60 will take up the position determined by the particular stop embraced by the locator bar 95 and the projection 98. So then to recapitulate. If we have a tabulator 125 stop protruded and the slideable piece 73 actuated, the universal totalizer 60 will be brought to a position dependent upon the tabulator stop which has been protruded.

As I have stated the columnar and univer- 130

sal totalizers are tabulated at the same time. The columnar totalizers being rigid with the carriage are tabulated with it. The universal totalizer is coincidently tabulated by 5 means of the linkage just described, and the power for so doing comes from the motor. After having been brought to their required positions both totalizers are rigidly connected together by means of the bar 63, and 10 move together in unison until after the insertion of the last digit of the required number. They then are disconnected and remain so until the next succeeding tabulation. Since this linking together by means of the 15 bar 63, moving in unison, and subsequent disconnecting of the universal totalizer from the columnar totalizer is exactly the same as that in my application above referred to, I shall not here describe them.

20 In Fig. 4 is shown the connection between the ordinary tabulator stops of the typewriter and the tabulator keys. Rod 106 has on its end a push button, not shown, and is one of the customary set of tabulating keys. 25 This rod is fastened to an individual lever 107 fulcrumed at 108. Lever 107 is connected by a rod 109 to tabulator stop 110 fulcrumed at 111 having an end 112 adapted to engage the ordinary tabulator lugs on the 30 carriage and a portion 113 which is engaged by the bars 94 and 96. There is one set of the above mentioned parts, 106, 107, 109, 110, 112 and 113 for each tabulator key. A universal bar 114 adapted to be moved by any 35 of the levers 107 is also fulcrumed at 108 and is connected by a link 115 to a rocker arm rigid with the shaft 117 fulcrumed in the frame work. Rigid with the shaft 117 is a bent lever 116 fulcrumed at 117. Consequently 40 considering the chain which connects lever 116 to the tabulator key 106, motion of the tabulator key 106 to the right (Fig. 4) will cause motion of the lever 116 to the left. Mounted on lever 116 is a stud 119. A link 45 120 has at one end a slot 121 sliding on the stud 119, and at the other end is pivoted on a lug 122 rigid with the slideable piece 73. Actuation of a tabulator key therefore will produce actuation of the slideable piece 73, 50 which it will be remembered releases the tabulator clutch thus starting in action the chain of mechanism which tabulates the universal totalizer.

When the columnar decimal carriage is 55 tabulated by the use of the tabulator keys, it is necessary to raise the rack 42 from the escapement gear 46. Accordingly the bent lever 116 is jointed by a rod 118 to the yoke 123 (Figs. 1 and 2) pivoted to the arm 39. 60 Motion of the bent lever 116 therefore causes rotation of the arm 39, about its fulcrum 49 and consequent disengagement of the rack 46 as previously described in this specification. The rod 118 is provided with a head 65 124, and telescopes into the yoke 123. It will

be remembered that when the carriage 25 is returned, the arm 39 is momentarily depressed. If the connection between the yoke 123 and the rod 118 were solid this might by actuation of the lever 116 release the tabulation clutch. This would be undesirable so the rod 118 and yoke 123 are constructed so that downward motion of the arm 39 will not affect the lever 116.

Having now described my invention I 75 shall call attention to some of its advantages. Taking up the carriage return portion first, it will be noted that the elastic stop which serves to bring the carriage quietly to rest at the end of the carriage return, is the usual 80 rack provided with the carriage. As ordinarily constructed this rack is mounted on a swinging arm and held in engagement with the escapement gear by means of a spring. In my construction this spring is utilized as 85 the elastic stop against which the carriage is brought to rest on its return. This construction is simpler than providing an additional piece to perform this function.

It will be noted that the link controlling 90 the carriage return clutch is adapted to be acted on from two sources. First the manual key which serves to start the carriage on its return, and second, the lever 36 which is engaged by the carriage on its return to its 95 predetermined position. These two parts just mentioned do not interfere with each other for it is obvious that upon the carriage returning to its predetermined position thus engaging the arm 36, the clutch will be disconnected regardless of the fact that the manual key 13 is still in a position to engage the clutch.

Attention is also called to the fact that in the chain of clutch disengaging linkage there 105 is a toggle joint so a slight displacement of the pivot 30 from its position in alignment with pivot 28 and fulcrum 27, will serve to break the toggle, the clutch will thereupon disengage itself.

The power tabulation for the universal totalizer is of advantage in that all the power necessary to tabulate this universal totalizer to its required position comes not from the tabulator keys but from the motor. It will be noted that the clutch controlling the connecting of the motor to the tabulating linkage is a nonrepeating clutch. On the displacement of any tabulating key from its normal position, the clutch will 115 cause the linkage to go through one cycle but no more. In order to cause this cycle to repeat the tabulator stop must first be restored to its normal position and then subsequently actuated, so that to each cycle 120 of the tabulating key corresponds one cycle of the locating linkage.

In this specification I have used the adjectives columnar and universal to describe two kinds of totalizers used in my inven- 130

tion. By columnar totalizer I mean a totalizer adapted to perform calculations on numbers arranged in vertical columns. By universal totalizer I mean a totalizer adapted to perform calculations on numbers arranged in any order, either vertical or horizontal. It will be observed also that in my present invention while the columnar totalizers can be tabulated in but one direction, namely, from right to left, the universal totalizer can be tabulated in either direction. The universal totalizer is usually tabulated from left to right but this is not necessarily so. The locating linkage will tabulate it in either direction.

It is obvious that while I have described a machine with columnar and universal totalizers the columnar totalizers are not at all necessary to my invention since they might be replaced by stops on the typewriter carriage, with which stops the connecting bar 63 would engage at the proper time.

In the particular type of adding machine described here the digits of the number are entered into the totalizers *seriatim*. This necessitates an element which moves step by step to determine the decimal place in which each digit is to be entered. In my present invention this element is the totalizer itself. It is obvious that the totalizer could be stationary and the master wheel move relatively thereto, or other means such as a movable stop operating on a set of triggers might be used to determine this decimal place.

It is obvious that my power tabulating mechanism could be applied to any of the constructions mentioned and I have therefore in the claims called the element which moves step by step to determine the decimal place in which each digit is entered, the decimal carriage and I wish it to be according so understood.

Many changes can be made in the details of my hereindisclosed construction without departing from the spirit of the invention.

Having thus described my invention I claim:

1. In a calculating machine the combination of: a locating linkage; a set of tabulator stops; a source of power normally disconnected from said locating linkage; and a clutch adapted to connect said source of power with said locating linkage upon the actuation of one of said sets of tabulator stops.

2. In a calculating machine the combination of a totalizer, an actuating mechanism therefor; a decimal carriage tabulatable in either direction to effect the appropriate decimal relation of said totalizer and actuating mechanism; a set of tabulator stops; a source of power normally disconnected from said carriage; and a clutch adapted to connect

said source of power with said carriage to bring it to a decimal place, determined by one of said stops.

3. In a calculating machine the combination of: a decimal carriage; a source of power normally disconnected from said carriage; a set of tabulator stops; and a clutch to connect said source of power with said decimal carriage on the actuation of any stop of said set, and thereby bring said decimal carriage to predetermined decimal place dependent upon the stop actuated.

4. In a calculating machine the combination of a totalizer, an actuating mechanism therefor: a decimal carriage tabulatable in either direction to effect the appropriate decimal relation of said totalizer and actuating mechanism; a source of power normally disconnected from said carriage; and a clutch to connect said source of power with said carriage to thereby bring said carriage to a predetermined decimal place.

5. In a calculating machine the combination of: a decimal carriage; a locating linkage therefor; a source of power normally disconnected from said linkage; and a clutch to connect said linkage with said source of power to bring said carriage to a predetermined decimal place.

6. In a calculating machine the combination of: a decimal carriage tabulatable in either direction; a locating linkage therefor; a source of power normally disconnected from said carriage; and a clutch to connect said locating linkage with said source of power for the purpose described.

7. In a calculating machine the combination of: a decimal carriage; a locating linkage therefor; a set of tabulator stops; a source of power normally disconnected from said locating linkage; and a clutch adapted to connect said source of power with said locating linkage and operated on the actuation of one stop of said set.

8. In a calculating machine the combination of: a decimal carriage tabulatable in either direction; a locating linkage therefor; a set of tabulator stops; a source of power normally disconnected from said locating linkage; and a clutch adapted to connect said source of power with said locating linkage and operated on the actuation of one of said sets of stops.

9. In a calculating machine the combination of: a locating linkage; a set of tabulator stops; a source of power normally disconnected from said linkage; and a non-repeating clutch adapted to connect said source of power with said locating linkage upon the actuation of any stop of said set.

10. In a calculating machine the combination of: a constant aggregate motion linkage; a set of tabulator stops; a source of power normally disconnected from said con-

stant aggregate motion linkage; and a clutch adapted to connect said source of power with said constant aggregate motion linkage upon the actuation of any stop of said set.

5 11. In a calculating machine the combination of: a constant aggregate motion linkage; a set of tabulator stops; a source of power normally disconnected from said linkage; and a non-repeating clutch adapted to 10 connect said source of power with said linkage upon the actuation of any stop of said set.

12. In a calculating machine the combination of: a locating linkage; a set of tabulator 15 stops; a source of power normally disconnected from said locating linkage; a clutch adapted to connect said source of power to said locating linkage upon the actuation of any one stop of said set; and means to disconnect said linkage from said source of power upon the completion of one cycle of 20 operation of said linkage.

13. In a calculating machine the combination of a totalizer: a decimal carriage; tabulating means to determine the particular decimal place of the totalizer; a source of power normally disconnected from said carriage; and a clutch adapted to connect said source of power with said decimal carriage to thereby bring it to the particular place determined by the tabulating means.

14. In a calculating machine the combination of a totalizer: a decimal carriage; tabulating means to determine the particular decimal place of the totalizer; a source of power normally disconnected from said carriage; and a clutch adapted to connect said source of power with said decimal carriage

upon the actuation of said tabulating means, to thereby bring said decimal carriage to the 40 particular place determined by said tabulating means.

15. In a calculating machine the combination of: a decimal carriage; a source of power normally disconnected therefrom; a 45 locating linkage connected with said carriage; a set of intrudable tabulator stops; and a clutch adapted to connect said linkage with said source of power upon the actuation of one of said tabulator stops, thereby locating said linkage in contact with the intruded 50 tabulator stops.

16. In a calculating machine the combination of: a locating mechanism; a set of tabulator stops; a source of power normally disconnected from said locating mechanism; and a clutch adapted to connect said source of power to said locating mechanism upon the actuation of one of said tabulator stops.

17. In a calculating machine the combination of a totalizer, an actuating mechanism therefor; a decimal carriage tabulatable in either direction to effect the appropriate decimal relation of said totalizer and actuating mechanism; a set of tabulator stops; a 60 source of power normally disconnected from said carriage; and a clutch adapted to connect said source of power with said carriage to bring it to a decimal place determined by 65 the actuation of any one of said stops.

In witness whereof, I have hereunto signed my name, this 20th day of August, 1912.

ARTHUR F. POOLE.
